UNITED STATES PATENT OFFICE.

CLARENCE C. SHIPP, OF INDIANAPOLIS, INDIANA.

ROOF-VENTILATOR JOINT.

1,336,590.

Specification of Letters Patent. Patented Apr. 13, 1920.

Application filed January 28, 1919. Serial No. 273,588.

To all whom it may concern:

Be it known that I, CLARENCE C. SHIPP, a citizen of the United States, residing at Indianapolis, in the county of Marion and State of Indiana, have invented certain new and useful Improvements in Roof - Ventilator Joints, of which the following is a specification.

This invention relates to certain improvements in a self sealing joint between the overlapping ends of that class of roof ventilators comprising an air exhaust duct and a hollow horizontally disposed revolute hood wherein the normal air currents 10 are directed transversely across the longitudinal axis of the duct for inducing an artificial draft through the latter; and one of the objects of the invention consists in the provision of a self sealing joint of the above 15 character whereby the intervening space between the overlapped ends of the duct and hood is sealed against the induction of air which in effect would impair the efficiency of the vacuum at the discharge end of the 20 duct and within the hood.

A further object of the invention consists in the provision of a joint of the above character which will impose a minimum frictional resistance; be simple in construction, efficient in operation, easy to repair and economical to manufacture.

I accomplish the above objects of the invention by means of the construction illustrated in the accompanying drawings, forming a part hereof, in which—

Figure 1 is a view partly in elevation and partly in vertical section of a roof ventilator of the revolute hood type, with my improved self sealing joint embodied therein. 40 Fig. 2 is an enlarged sectional detail view of the overlapped ends of the stationary ventilator duct and hood, showing more clearly the construction and arrangement of my improved joint.

Referring to the drawings, 10 represents the vertically disposed stationary ventilator duct which projects through the roof of the building. The revolute hood comprises a vertically disposed tube 11 which, while 45 forming a continuation of duct 10, is larger in diameter than the latter end is arranged so that its lower end overlaps the upper end of duct 10, as shown. Tube 11 communicates with a horizontally disposed pipe 12 50 having a truncated cone 13 arranged therein, the base of the cone being secured to the

inner surface and near one end of pipe 12. A vane 15 is secured to the top of pipe 12 for constantly maintaining the enlarged end of cone 13 adversely to the normal travel 60 of the prevailing air currents, and as these currents discharge from the reduced end of cone 13 a vertically movable draft is induced in ventilating duct 10. As the induced draft through duct 10 is the result 65 of a vacuum of slightly varying degrees of intensity within tube 11, this vacuum is easily impaired depending on the amount of air admitted other than at the inlet end of duct 10, so that the efficiency of this type 70 of ventilator as a ventilating medium is considerably reduced. The above objections are the result of the necessary loose joint between the walls of the overlapping ends of the duct and tube, leaving the hood free 75 to readily shift position as the air currents change their direction of travel. To overcome the bad effect of the loose joint above mentioned and still permit free action of the hood is one of the chief features of the 80 present invention, and this I accomplish by providing a simple self sealing joint comprising a ring 20 which is composed of yieldable material such as felt or other fabric which is bent down over the edge of the 85 upper end of duct 10, as shown in the drawings, and ring 20 is held against accidental displacement by means of a collar 21. The outer portion of the felt or fabric ring 20 extends outwardly from the outer peripheral wall of duct 10 and in a downwardly 90 inclined angle with the peripheral edge of the ring slightly contacting the internal wall of tube 11 of the hood through its contact with the raised surface of an outwardly 95 disposed rib 22 formed in the wall and near the upper end of duct 10. By means of its yieldability felt ring 20 is readily susceptible of movement under the influence of the vacuum above it in tube 11, so that the more 100 readily the air is removed from tube 11 the more firmly the peripheral edge of collar 20 will bear against the adjacent internal wall of said tube.

The revolute hood, comprising tube 11 and pipe 12, is retained in operative position by means of a vertically disposed shaft 25 which is supported by the hood by means of the radial arms 26. Shaft 25 is also provided with a cone-bearing member 27 which 110 rides on a ring 29 supported on balls 30 which are arranged in the upper end of a

stationary sleeve 31, and the latter is supported in duct 10 by the radial arms 32. The lower end of shaft 25 is arranged in a stationary sleeve 33 which is secured to duct 10 by means of the radial arms 34. The lower end of sleeve 33 affords a seat for suitable balls 35, and the lower end of shaft 25 is provided with a cone-bearing member 36 which contacts a bearing ring 37 riding against the balls 35, so that the two bearings constantly hold the shaft 25 in vertical operative position.

Having thus fully described my said invention, what I desire to secure by Letters Patent, is—

- 15 1. A ventilator of the class described comprising an air exhaust duct, a revoluble hood overlapping the adjacent end of the duct and receiving the discharge of the latter, and a yieldable means having movement induced by the upwardly moving draft in the duct for closing the space between the adjacent walls of the overlapped ends of the duct and hood.
- 20 2. A ventilator comprising an air exhaust

duct, a revoluble hood overlapping the adjacent end of said duct, yieldable means yieldingly moving under the influence of the draft through the duct for closing the space between the adjacent walls of the overlapped ends of the duct and hood, and means for preventing accidental displacement of said yieldable means.

3. A ventilator of the class described comprising an air exhaust duct, a revoluble hood overlapping the adjacent end of the duct and receiving the discharge of the latter, and a yieldable means arranged between the adjacent walls of the overlapped ends of the duct and hood and actuated by the draft through the hood for closing the space against leakage of air between the adjacent walls of the overlapped ends of the duct and hood.

In witness whereof I have hereunto set my hand and seal at Indianapolis, Indiana, this 25th day of January, A. D. one thousand nine hundred and nineteen.

CLARENCE C. SHIPP. [L. S.]
